UNITED STATES PATENT OFFICE.

THOMAS W. CRENSHAW AND WILLIE J. CRENSHAW, OF CLARKSVILLE, TEXAS.

FIGURE TOY.

Application filed April 30, 1921. Serial No. 465,676.

To all whom it may concern:

Be it known that we, THOMAS W. CRENSHAW and WILLIE JOHNSON CRENSHAW, citizens of the United States, residing at 5 Clarksville, in the county of Red River and State of Texas, have invented certain new and useful Improvements in Figure Toys, of which the following is a specification, reference being had to the accompanying drawings.

This invention relates to figure toys and more particularly to a wind operated figure toy.

An important object of the invention is to 15 provide a device of this character which may be employed as an ornament upon the radiator of an automobile.

A further object of the invention is to 20 provide a device of this character wherein by the operation of a wind wheel associated with the device a figure toy embodied therein resembling a man is caused to apparently actuate a crank shaft to rotate the wind wheel.

25 A further object of the invention is to provide a device of this character wherein the operation of the figure toy is made at a reduced speed to prevent undue wear thereof.

30 Other objects and advantages of the invention will become apparent throughout the course of the following description.

Figure 1 is a side elevation of a toy constructed in accordance with our invention; 35 and

Figure 2 is a transverse sectional view taken therethrough and illustrating the manner of supporting the toy body during bending thereof.

40 Referring now more particularly to the drawings, the numeral 10 indicates a substantially vertical standard adapted to be secured to the filling cap of an automobile radiator, and having pivoted upon the upper end thereof a horizontally swinging support bar 11. The support bar 11 is provided at one end thereof with a tail for guiding a vane 12 whereby the opposite end thereof is directed into the wind, and the last named 45 end carries a wind wheel 13 having a pinion 14 secured upon the shaft 15 thereof, the shaft 15 being rotatably mounted in the bar 11.

Extending upwardly from the upper surface of the bar 11 are spaced supports 16 in 50 which is rotatably mounted a crank shaft

17, the forward end of the crank shaft 17 having secured thereto a gear 18 of relatively large size meshing with the pinion 14 of the shaft 15. It will be seen that upon 60 rotation of the wind wheel 13 the shaft 17 will be driven at a materially reduced speed.

Extending outwardly from the bar 11 at the side thereof is a horizontal support 19 to which are secured rigid vertically extending legs 20 of a figure toy. Intermediate the upper extremities of the legs a body member 21 having a head rigid therewith is pivoted, and to the body portion 21 arm members 22 of the figure toy are pivoted. The 70 adjacent portion of the shaft 17 is provided with a crank 23 upon which the free ends of the arms 22 are rotatably mounted.

In the operation of the device the rotation of the wind wheel causes the shaft 17 to be 75 slowly rotated so that the figure toy apparently turns the crank 23, the body of the toy bending from the hips in very close resemblance to human actions in rotating the crank. The head 21^a of the figure toy 80 is provided with a projection 24, in the present instance made in the resemblance of a cap peak, which is so alined with the crank 23 that it prevents excessive pivotal movement of the body during the bending thereof and particularly at that point of the bending of the body at which the arms are 85 furthest outstretched from the body portion. Were this engagement not provided the wear upon the pivotal connections of the 90 arms and legs would in a short while permit the body to sag to such a degree that the body would drop below its proper position and would cause the toy to become inoperative.

95 From the foregoing it is believed to be obvious that we have constructed a figure toy which is particularly well adapted for the use for which it is intended by reason of the fact that means are provided for the 100 prevention of excessive wear upon the bearings thereof, thereby rendering the top relatively long-lived. It will furthermore be obvious that the construction hereinbefore set forth is capable of some change and 105 modification without departing from the spirit of our invention, and we accordingly do not limit ourselves to the specific structure thereof except as hereinafter claimed.

110 What we claim is:

1. In a wind-operated figure toy, a support, a member pivoted to the support to

swing in a horizontal plane and provided at one end thereof with a guiding vane, a shaft rotatably mounted in the opposite end of the member and having a wind-wheel secured thereto, braces extending upwardly from the member, a crank shaft rotatably mounted in the braces, a driving connection between the wind wheel and crank shafts, horizontal braces extending outwardly from the side of the member, a figure toy embodying legs rigidly secured to said horizontal braces, a body pivotally connected to the upper end of the legs, and arms pivotally connected to the body and having the free extremities thereof pivotally connected with the crank of said crank shaft, said body embodying a head having a projection thereon adapted to engage against the crank of the crank shaft to support the body and prevent excessive pivotal movement thereof.

2. In a wind-operated figure toy, a support, a member mounted thereon to swing

horizontally and provided at one end with a guiding vane, a shaft rotatably mounted in the opposite end of the member and having a wind-wheel secured thereto, a pinion on said shaft, a crank shaft mounted on the member and having a relatively large gear wheel meshing with the pinion, a figure embodying legs rigidly and operatively mounted on said member, a body pivotally mounted on the upper end of the legs, arms pivotally connected to the body and having their extremities pivotally connected with the crank of the crank shaft, said body embodying a head, and a projection carried by the head and being of a length adapting it to engage against the crank of the crank shaft to prevent the body from dropping below its proper position.

In testimony whereof we hereunto affix our signatures.

THOMAS W. CRENSHAW.
WILLIE J. CRENSHAW.
